UNITED STATES PATENT OFFICE

2,091,442

OIL BURNER DOOR

Sidney J. Heiman, St. Louis, Mo.

Application October 28, 1936, Serial No. 107,973

3 Claims. (Cl. 110—173)

The specific object of my invention is to make a door for oil burners. In oil burners it is necessary to have a door positioned in the fire box, in order to give selective access to the burners 5 in the fire box. The door, when closed, must form a perfect seal so as not to admit air into the fire box. This is essential in order not to disturb the combustion or circulation of heated air in the fire box. The door may be used equally 10 well in gas, coal or wood burners.

In order to form a perfect seal between the door and fire box opening, careful machining of the face of the door and the face of the fire box opening is necessary, but in the ordinary 15 methods of manufacture, it is not possible to have these faces machined sufficiently exactly to form a perfect seal. If the surfaces of the door and those surrounding the fire box opening are not fitted exactly, air will leak between the 20 surfaces from the outside of the door into the fire box. Furthermore a slight warping of the fire box opening will make even an imperfect seal impractical with the conventional door.

Furthermore the door structure must be such 25 that no practical care is necessary in locking the door, in order to close it tightly, because the ordinary user of the oil burner will not exercise the amount of care that is necessary to tightly close an ordinary door. The structure must be 30 simple and inexpensive, and lend itself readily to multiple production. The structure herein described meets all these requirements. With these and other objects in view, my invention has relation to certain novel features of construction 35 and arrangement of parts, as will be hereinafter more fully described, pointed out in the claims and illustrated in the drawing, in which

Fig. 1 is a front elevation of the frame and door, together with its jointure means to the fire 40 box of an oil burner.

Fig. 2 is a top plan view showing the door in its opened position.

Fig. 3 is an enlarged central, vertical, sectional view, partially in elevation.

Numeral 4 designates the fire box opening of 45 the fire box 5. The fire box 5 is made in the usual manner with the tapered wall 6. Numeral 7 designates lugs formed on the fire box 5 on each side thereof at the bottom, having a hole 8 formed therein. Numeral 9 is the outer door, which is hingedly secured to the lug 7, by means 50 of the threaded bolts 10 passing through a hole in the outer door 9 and the hole in the lug 7.

On the fire box 5, at the top, adjacent the fire 55 box opening 4, is formed the lug 11. The outer

door 9 is formed by the vertical wall 12, which has the flanges 13 formed thereon. Numeral 14 designates openings in the outer door 9.

Means of locking the outer door 9 to the fire box 5 are the following:

A pin 15 is in rotative engagement in a hole 16 formed in the outer door 9 centrally near the top. The handle 16' is secured to the external end of the pin 15. Numeral 17 designates a finger secured to the inner end of the pin 15 by means 10 of the set screw 18. The pin 15 is of such length and the finger 17 is secured to it at such a position, that when the outer door 9 is in its closed position the finger 17 will be in frictional engagement with the inner face of the lug 11.

Finger 17 has a cam face 17' for engagement with lug 11, to pull door 9 up tight.

The structure thus far described is conventional. Applicant's invention consists in the following structure per se and in combination with 20 the structure thus far described:

Numeral 19 designates an inner door. Centrally positioned interiorly on the outer door 9 integrally is formed the fragment of a sphere 20. Numeral 21 designates a projection on the inner 25 door 19. In the projection 21 is formed the spherical cavity 22. The spherical cavity 22 and the fragment of the sphere 20 are of such shape and size that the fragment of the sphere 20 fits on the spherical cavity 22 exactly, the fragment 30 of a sphere and the spherical cavity 22 forming a ball and socket joint.

Numeral 23 designates a screw passing through the projection 21 of the inner door 19 and into the center of the fragment of a sphere 20. The 35 screw 23 is not secured tightly in the inner door 19, but sufficiently loosely that the inner door 19 may be rocked on the fragment of the sphere 20 within narrow limitations. Numeral 24 designates the face of the fire box opening with which 40 the face of the inner door 19 will come into engagement when the outer door 9 is closed. In order to limit the movement of the inner door 19 on the fragment of the sphere 20, lugs 25 are formed on the inner door 19 between the inner 45 door 19 and the inner face of the vertical frame 12 of the outer door 9. Lugs 26 are formed on the inner face of the vertical wall 12 of the outer door 9. The thickness of the lugs 25 and 26 are slightly less than the distance between the outer 50 face of the inner door 19 and the inner face of the outer door 9. The lugs 25 and 26 are staggered, so as not to come into contact with each other. The space between the lugs 25 and 55 the inner face of the vertical wall 12 is the same 55

as the space between the lugs 26 and the outer face of the inner door 19. This distance represents the amount of possible rotation of the inner door 19 on the fragment of a sphere 20.

- 5 5 Glazed openings 27 in the inner door 19 register with the opening 14' in the outer door 9.

It will be observed that when the structure thus far described is assembled as indicated, provided the parts are made of substantially the 10 size herein described and illustrated in the drawing, that when the outer door 9 is closed that the inner door 19 will be closed. It is obvious that by the structure described that the inner door 19 becomes centered over the fire box opening 4, and that if there are any differences in 15 size, through warping or otherwise of the surfaces in contact between the inner door 19 and the face of the fire box opening 4, that the inner door 19 will be slightly rocked on fragment 20 of a sphere 20, forming a perfect seal between the inner door 19 and the face of the fire box opening 24.

What I claim and mean to secure by Letters Patent is:

- 25 1. In combination with a fire box, an outer door hingedly secured thereto, an inner door secured to said outer door by means of a ball and socket joint, means of locking said outer door to said fire box and simultaneously securing said 30 inner door against the faces of the opening of said fire box, lugs secured on the inner face of said outer door and on the outer face of said inner door for limiting the possible oscillating of said inner door on said outer door.

- 35 2. In combination with a stove having an opening therein, an outer door hingedly secured thereto in operative position relative the opening in

said stove, an inner door secured to said outer door by means of a ball and socket joint, means of locking said outer door to said stove over the opening in said burner and simultaneously securing said inner door against the faces of the opening in said stove, lugs secured on the inner face of said outer door and on the outer face of said inner door for limiting the possible oscillation of said inner door on said outer door.

3. In combination with a stove having an 10 opening therein, an outer door hingedly secured thereto in operative position relative the opening in said stove, an inner door secured centrally and interiorly to said outer door by means of a ball and socket joint, one portion of which 15 is secured to said outer door and the other portion of which is secured to said inner door, the portions of said ball and socket joint being secured together in a rocking manner by means of a screw passing through one portion to the other portion, means for locking said outer door to said stove over the opening therein, and simultaneously securing said inner door against the faces of the opening in said stove, lugs formed on the inner door between the inner door and the 20 inner face of the vertical frame of the outer door, and similar lugs formed on the inner face of the vertical wall of the outer door, the thickness of said lugs being slightly less than the distance between the outer face of the inner door 25 and the inner face of the outer door, the lugs on the inner door being staggered relative the lugs on the outer door, said lugs so constructed as to limit the possible oscillation of said inner door on said outer door.

SIDNEY J. HEIMAN.
